UNITED STATES PATENT OFFICE.

WADE H. WINEMAN, OF MICHIGAN CITY, INDIANA, ASSIGNOR TO SULLIVAN MACHINERY COMPANY, A CORPORATION OF MASSACHUSETTS.

DRILL-FORGING MECHANISM.

Application filed April 28, 1925. Serial No. 26,446.

This invention relates to drill forging mechanism and more particularly to a punch for hollow drill steels.

In forming the bit of a hollow drill steel the hollow portion becomes closed and a suitable mechanism must be provided to open the same which is customarily done by having an elongated punch adapted besides opening the hole to enlarge the same beyond its normal size if necessary. Due to varying conditions such as different lengths of steel or punch, considerable movement of the punch will sometimes take place before actually engaging the steel or before the same has been completely withdrawn therefrom. In the punching mechanism herein specifically disclosed, a pneumatic hammer is employed and it is of course unnecessary to actuate said hammer until the punch has actually engaged the steel. It is accordingly an object of the invention to provide improved means whereby the pneumatic hammer will not be actuated until the punch actually engages the steels regardless of the amount of punch movement necessary to cause said engagement, which manner of operation is in distinction to those punching mechanisms wherein the hammer is actuated soon after if not immediately upon forward movement. A further object is to provide improved means whereby the punch may be fed forwardly and if desired said means can be used to withdraw the pin from the steel.

In the accompanying drawings I have shown for purposes of illustration one form which my invention may assume in practice.

In these drawings,—

Fig. 1 is a side elevation of a forging machine with my improved punching mechanism thereon.

Fig. 2 is a fragmentary plan view of the punching and steel clamping mechanism.

Fig. 3 is a longitudinal sectional view of the pneumatic hammer for the punch.

Fig. 4 is a plan view thereof partly broken away to show details of construction.

Fig. 5 is an end view of the hammer.

In the illustrative embodiment of the invention I have shown the same associated with a drill sharpener generally indicated at 1 and of a well known type. As the specific details thereof do not enter into the present invention, it will suffice to say that the same has cooperating relatively movable clamping jaws 2 and 3 having laterally overhanging

upper and lower lips 4 and 5 adapted to clamp a drill steel 6 with its bit end 7 adjacent a punch mechanism 8. This mechanism comprises a frame 9 suitably mounted upon the rear portion of the forging machine 10 frame 1 and has guide grooves 10 to receive lips 11 of a movable hammer base 12. The hammer comprises a cylinder 13 provided with a chuck 14 to receive the shank 15 of a collared punch 16 which is hammered upon by a hammer piston 17 reciprocably actuated by fluid controlled by a suitable valve mechanism 18. A rear main controlling valve supporting head 19 has threaded engagement with the rear end of the cylinder 13 and is adapted with the cylinder 13 to slide relative to the base 12 due to suitable supporting means herein comprising a collar 20 disposed between lugs 21 carried on the base 12. The front end of the cylinder 13 is slidably guided by a guide 22 horizontally split, although it will be clear that a steel punch support 23 carried by the base 12 could be used alone to support the front end of the punching mechanism. A link 24 is pivotally connected at its respective ends to the support 23 and arm 25 of a pin puller device having a hand lever 26 pivotally supported upon the frame 1. As shown in Fig. 2, the arm 25 has a bifurcated portion 27 and can be used to withdraw a stuck punch pin from the steel in case it is impossible to remove the pin while remaining in the hammer as shown in Fig. 3.

Disposed within the head 19 is my improved means for automatically controlling actuation of the hammer in accordance with feeding thereof. This means comprises a longitudinal passage 28 communicating with the valve mechanism 18 and a transverse fluid inlet passage 29 to which fluid is supplied through a nipple 30 extending through a slot 31 formed in the head 19. A longitudinal valve bore 32 traversing the opening 29 receives a two spool valve 33 having an annular space 34 adapted when in the position shown in Fig. 3 to allow flow of fluid from the nipple 30 to a passage 28 and thereby actuate the piston 17, although when in the position shown in Fig. 4 fluid is shut off to prevent operation of the hammer. It is to be noted that in this latter position the cylinder and head 19 are disposed away from the end portion of the collar 20.

In operation of the device, the steel will

be clamped between the lips 4 and 5. Pulling down the lever 26 causes forward movement of the base 12 and cylinder, it being noted that during such operation the valve 33 is in a position as shown in Fig. 4 and accordingly no air will flow to the hammer. As long as the punch does not engage the steel to cause rearward movement of the head 19 relative to the collar 20, the hammer mechanism may be fed forward any distance without actuation thereof. However, upon engagement of the punch and steel, the hammer cylinder will be held stationary while the base 12 continues to move forwardly, whereupon the collar 20 will force the valve 33 forwardly to allow flow of fluid from the nipple 30 through passages 29 and 28 to actuate the hammer piston, whereupon the punch will be hammered into the opening. Should the punch stick upon attempt to withdraw the same, it is possible by having the link 24 of sufficient compression strength to exert sufficient force to remove the pin by use of the handle 26. If it is desired for any reason to want to utilize the motor for withdrawing the pin, suitable mechanism could of course be employed, but as a part of the gist of the present invention is to provide improved means whereby the punch will not be operated until having actual engagement with the steel, I have not disclosed this other well known mechanism. If for any reason, as before said, the punch is irremovable from the steel, then the punch may be removed while in the steel and the steel placed in its reverse position between the clamping jaws 4 and 5 to permit engagement of the punch collar by the bifurcated portion 27, whereupon great force may be exerted to withdraw the punch pin.

While I have in this application specifically described one form which my invention may assume in practice, it will be understood that this form has been shown for purposes of illustration and that the invention may be modified and embodied in various other forms without departing from its spirit or the scope of the appended claims.

What I claim as new and desire to secure by Letters Patent is:

1. A drill steel punch mechanism comprising a fluid actuated hammer punch, means for slidably supporting the same, mechanical means for feeding said hammer punch forwardly, and means whereby the same is automatically actuated upon actual engagement with a steel including a controlling valve initiating fluid flow to the punch hammer on engagement of the punch with a steel.

2. A drill steel punch mechanism comprising a fluid actuated hammer punch, means for slidably supporting the same, mechani-

cal means for feeding said hammer punch forwardly, and means whereby the same is automatically actuated only upon actual engagement with a steel. 65

3. A hollow drill steel punch mechanism comprising a punch, a fluid actuated hammering motor cooperating therewith, means for supporting and guiding the same for longitudinal movement relative to a drill steel, said motor and punch being mounted on said supporting means for movement 70 relative thereto, manual means for moving said supporting means toward the drill steel and for further moving said supporting means after engagement of the punch with the drill steel, and means for rendering said 75 hammer operative only upon said further movement. 80

4. A drill steel punching mechanism comprising a slidable base, a hammer actuated punch carried thereby and movable relative 85 thereto, means connected to said base for slidably moving the same and said punch, and means for controlling the operation of said punch functioning on relative movement between said base and punch when the 90 punch engages a drill steel.

5. In combination, drill steel clamping mechanism, a base movably supported adjacent said mechanism, and punching mechanism carried thereby including elements 95 respectively fixed and movable relative to said base, and means whereby said punch is rendered operative only upon engagement with a drill steel.

6. In a drill steel punching mechanism 100 comprising a hammering motor having a valve mechanism associated therewith for controlling its operation, means for supporting said motor, said support being engageable with said valve mechanism to cause actuation thereby on relative movement of said motor and support, and means for manually moving said support, said means adapted to effect said relative movement upon engagement of said punch with a drill steel. 105

7. The combination with a pin puller mechanism including an operating lever, of a drill steel punching mechanism comprising a fluid actuated hammer punch, and means operatively connected to said pin 110 puller lever for feeding said punch forwardly.

8. The combination with a pin puller mechanism including an operating lever, of a drill steel punching mechanism comprising a fluid actuated hammer punch, means operatively connected to said pin puller lever for feeding the punch forwardly, and means whereby the punch is actuated only upon actual engagement with a steel. 115 120

In testimony whereof I affix my signature.

WADE H. WINEMAN.
